UNITED STATES PATENT OFFICE.

HELEN L. SHAFFER, OF CHICAGO, ILLINOIS.

CATAMENIAL BAND.

Application filed October 22, 1924. Serial No. 745,244.

My invention relates to belts adapted to encircle the human body, and is devised more particularly for use as a catamenial belt.

It has for its principal object a belt which will at once conform to the shape of the body, will not fold or wrinkle, is always soft and pliable and by reason of its flexibility is readily adjustable to a variety of sizes and shapes of individuals.

10 It is also an object of my invention to provide a belt of this kind which shall be formed of a single piece of material, having formed integrally therewith tabs which extend downwardly at the center back and center 15 front of the belt, to which may be attached any suitable bandage or supporting member.

In the accompanying drawings, I have illustrated what I now consider the preferred and simplest form of an embodiment of the 20 essential features of my invention and in these drawings, the figure represents a perspective view of my belt.

Referring to the drawing, A, represents the belt which may be formed of any width 25 and length desired, and which is constructed of a knitted fabric, such as is used in wool stockings and the like, and preferably loosely knitted to provide elasticity in the body of the belt, which elasticity extends lengthwise 30 and crosswise of the belt.

At the center of the front *a* and the center of the back *a'*, I provide upon the lower edge of the belt an attaching tab, *b*—*b'*, to which may be secured any form of bandage desired 35 to be used. These tabs *b*—*b'* are formed in-

tegrally with the belt and as constructed have the same degree of elasticity as the body of the belt and is readily adapted to the movements of the person when worn. The meeting ends of the belt are provided with any 40 desirable form of fastening device, such as the snap fastener, *c*—*c*, shown in the drawing, although it is obvious I do not desire to be limited to this form of securing means as any 45 other well known fastening device, such as buttons, hooks and eyes, lacings and the like, may be used with the same result. As constructed, the belt readily conforms to the shape of the body of the person wearing it, forming no creases or uncomfortable lines on 50 the body.

I claim:

A belt for the purpose described, comprising a wide and flat tubular knit textile fabric band elastically yieldable longitudinally and 55 transversely, said band being of material width such as will conform to the body of the wearer without liability of wrinkling or rolling into the condition of a thin narrow string when in use, the bottom edge of the band being extended downwardly at the front and back into depending tabs for the attachment thereto of the front and rear ends of a bandage, said tabs being of tubular knit fabric and integral continuations of the tubular 60 knit fabric band.

In testimony whereof I have signed this specification.

HELEN L. SHAFFER.
